UNITED STATES PATENT OFFICE

FREDERICK ROSENBERG, OF KEW GARDENS, NEW YORK, ASSIGNOR TO WILLIAM
WILLHEIM CO., INC., OF NEW YORK, N. Y.

DESIGN FOR A TEXTILE FABRIC OR SIMILAR ARTICLE

Application filed October 14, 1932. Serial No. 45,337. Term of patent 3½ years.

To all whom it may concern:

Be it known that I, FREDERICK ROSENBERG, a citizen of the United States of America, residing at 118-80 Metropolitan Avenue, Kew Gardens, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design. The portion shown

within the dot and dash lines AB, BC, CD and DA incloses a complete unit of the design which is repeated in the relationship wherein angle B is repeated at B¹ and angle C is repeated at C¹.

I claim:

The ornamental design for a textile fabric or similar article as shown and described.

In testimony whereof I have signed this specification.

FREDERICK ROSENBERG.
